UNITED STATES PATENT OFFICE.

DANIEL R. BRADLEY, OF NEW YORK, N. Y.

DESIGN FOR A FLASK AND BOTTLE.

SPECIFICATION forming part of Design No. 14,423, dated November 20, 1883.

Application filed June 29, 1883. Term of patent 14 years.

To all whom it may concern:

Be it known that I, DANIEL R. BRADLEY, a citizen of the United States, residing at New York, in the county and State of New York, have invented and produced a new and original Design for Flasks and Bottles, of which the following is a specification.

The leading feature of my design consists in two flasks or bottles united side by side by means of a frame, so as to form a double receptacle.

In the accompanying drawings, which form part of this specification, I have represented my new design as particularly adapted for the reception of perfumes.

In the drawings, Figure 1 is a front elevation, and Fig. 2 a plan.

A A are two flasks or bottles, each having three shoulders or offsets—one near the bottom, one in plane of division separating the body of the flask from the neck, and one near the top of the neck. Between these flasks A,

at the levels of the several shoulders, extend flat strips or bridges $b b' b''$, each terminating at both of its ends in rings which encircle the flasks at the place of their shoulders, as clearly represented. At or near the middle of their length these bridges $b b' b''$ are made wider, the lateral swells being rounded, and between these widened portions extend upright cylindrical pieces $b^3 b^5$, the piece b^3 being formed with an enlarged portion or swell, b^4 .

C C are caps closing the mouths of the bottles, and having small openings closed by smaller caps c c.

I claim—

The design for flasks and bottles, consisting of the configuration substantially as shown and described.

DANIEL R. BRADLEY.
